UNITED STATES PATENT OFFICE.

JUAN LLOBET, OF HABANA, CUBA.

SAFETY-RAZOR BLADE.

Application filed June 23, 1925. Serial No. 39,107.

To all whom it may concern:

Be it known that I, JUAN LLOBET, a citizen of the United States, and a resident of Habana, Cuba, have invented certain new and useful Improvements in Safety-Razor Blades, of which the following is a specification.

This invention aims to provide an improved safety razor blade wherein means is provided to positively indicate use of the blade whereby to prevent palming off of old blades as new, no matter how cleverly these blades may be reconditioned, wrapped and packaged.

A further object resides in the provision of a blade of this character which has these advantages and capacities without altering in any substantial way the structural features of the blade or necessitating any departure from its ordinary mode of use.

A still further object of the invention is to provide a blade of this character which is of such a simple and practical construction as to have the advantages mentioned without adding to the cost of the blades, the metal ordinarily scraped being utilized to serve the purposes of the present invention.

Other objects and advantages reside in certain novel features of the construction, arrangement and combination of parts which will be hereinafter more fully described and particularly pointed out in the appended claims, reference being had to the accompanying drawings forming a part of this specification and in which:

Figure 1 is a plan view of a safety razor blade constructed in accordance with the present invention.

Figure 2 is a view thereof in transverse section.

Figure 3 is a view partly in section and partly in elevation showing how the assembly of the blade with the cap piece or backing alters the formation of the blade to indicate its use, and

Figure 4 is a view partly in section and partly in elevation showing how the blade in assembly coacts with the razor in the conventional manner.

Referring to the drawings the numeral 1 designates a razor blade having the usual body portion 2 on which cutting edges 3 are formed. In the central portion of the body

1 of the blade an opening 4 is provided to 55 accommodate the threaded bolt 5 of the usual cap or backing 6 employed for clamping the blade 1 on the head 7 of the razor blade. Positioning pins 9 are provided on the cap or backing 6 to properly position 60 the cap and blade on the head. All of this is the standard and conventional construction.

The present invention proposes the provision of lugs 10 in the openings 11, the lugs 10 being stamped from the metal of which the blade is formed and being connected with the blade by reduced and frangible connecting portions 11. Centrally 70 each lug is formed with centering apertures 12 designed to be engaged by the positioning pins 9 as shown in Figure 3 when the blade is assembled with the cap or backing 6 so that the assembly of the blade with the razor will necessarily result in the breaking off of the lugs 10. The presence of the lugs 10 affords an indication that the blade has never been used while their absence is 75 evidence of the use of the blade. In this way the reconditioning and repacking of 80 old blades and the palming off of such old blades on the public as new blades is prevented.

These advantages are had without altering the structure of the blade or its mode of operation when in use. Figure 4 shows that the blade is assembled with the razor exactly as the conventional blade. Since the lugs 10 are formed of the material from which the blade is stamped the cost of the blade is 85 not increased and yet fraud on the public 90 is prevented.

I claim:

1. A safety razor blade having a defined structure and also having means embodied 95 in the blade structure and separable and independent of the operative elements of the blade, said means being permanently altered when the blade is used to indicate that the blade has been used.

2. A safety razor blade having a frangible element integral therewith and separate and independent of the operative elements of the blade and adapted to be broken off from the blade when the blade is used to 100 indicate that the blade has been used.

3. A safety razor blade having an opening and an element extending into said

opening and adapted to be broken off when the blade is used to indicate that the blade has been used.

4. A safety razor blade having the usual 5 positioning pin openings and having elements extending into said openings and adapted to be broken off by the positioning pins of the razor when the blade is used to indicate that the blade has been used.
- 10 5. A safety razor blade having the usual positioning pin openings and having lugs stamped from the material of the blade and disposed in said openings, said lugs having frangible connecting portions connecting the same with the body of the blade whereby the lugs are adapted to be broken off by the positioning pins when the blade is used to indicate that the blade has been used.
- 15 the same with the body of the blade whereby the lugs are adapted to be broken off

by the positioning pins when the blade is used to indicate that the blade has been used.

6. A safety razor blade having the usual 20 positioning pin openings and having lugs stamped from the material of the blade and disposed in said openings, said lugs having frangible connecting portions connecting the same with the body of the blade whereby the lugs are adapted to be broken off by the positioning pins when the blade is used to indicate that the blade has been used, said lugs having centering apertures for the positioning pins.

JUAN LACBED.
